PROCESS AND APPARATUS FOR MONITORING SYNCHRONIZING GENERATORS

Harold Edward Beste, East Rutherford, N. J., assignor to Allen B. Du Mont Laboratories, Inc., Passaic, N. J., a corporation of Delaware

Application February 13, 1945, Serial No. 577,699

10 Claims. (Cl. 315—9)

1

This invention relates to a device and process for monitoring generators that are synchronized. The invention is particularly useful for monitoring sawtooth wave generators used in television but it is not limited to this use.

Heretofore television synchronizing generators have been monitored by using a cathode-ray tube of which the horizontal sweep was derived from an independent sweep circuit which was synchronized with the circuit that produced the wave form to be viewed on the cathode-ray tube. The horizontal sweep was adjusted so that two or three wave forms of the circuit being monitored could be viewed. The dividing ratio of the monitored circuit was determined by counting the number of pulses, on the sawtooth wave form, generated by the previous circuit which fired it. By the above method it was necessary to switch to one oscillator at a time, adjust the sweep, and adjust synchronization controls. The switching of the synchronizing pulses and wave forms to the monitoring device was necessarily complicated in that the sweep frequency also had to be changed by switching in different components when switching from one oscillator to another.

By the present invention the operation of all of the frequency dividing stages of a synchronizing generator can be shown simultaneously in such a way that it is immediately known when adjustments are needed, and also when proper adjustments have been made. By this invention the monitoring system is greatly simplified, extra tubes, switches and other components formerly used are eliminated, and a much more satisfactory monitoring system is provided.

The invention may be understood from the description in connection with the accompanying drawing, in which:

Fig. 1 is a somewhat diagrammatic arrangement of apparatus for carrying out the invention; and

Figs. 2 and 3 are diagrams showing patterns that appear upon the faces of cathode-ray tubes that enable the oscillators to be monitored.

In the drawing, reference characters 1 and 2 indicate cathode-ray tubes each having a cathode 3, control grid 4, and first and second anodes 5 and 6. Tube 1 has vertical deflection plates 7 and 8 and horizontal deflection plates 9 and 10. Tube 2 has vertical deflection plates 11 and 12, and horizontal deflection plates 13 and 14. The tube 1 is provided with the usual luminous screen 17 on the inside surface of the end thereof which is caused to be scanned by the beam or ray 15 of electrons. The tube 2 is provided with the

2

screen 18 which is scanned by the ray or beam 16.

Lead 26 extends from the oscillator 20 to the control grid 4 of tube 1, lead 27 extends from the oscillator 21 to the vertical deflection plate 7, and the lead 28 extends from the oscillator 22 to the vertical deflection plate 8. The horizontal deflection plate 9 is grounded and a lead 29 extends from the oscillator 23 to the horizontal deflection plate 10. Lead 31 extends from the oscillator 23 to the vertical deflection plate 11 of tube 2, lead 32 extends from oscillator 24 to the vertical deflection plate 12, lead 33 extends from oscillator 25 to the horizontal deflection plate 13, and the horizontal deflection plate 14 is grounded.

15 A 60 cycle source of power 35 is connected to the control grid 4 of tube 2 by lead 36.

The operation will be described specifically, using frequencies that are at present standard although the invention is useful with other frequencies.

20 The horizontal sweep on tube 2 is produced by applying a sawtooth voltage of 60 cycles per second from oscillator 25 to the horizontal deflection plate 13. Its length of time is one-sixtieth of a second as indicated by the horizontal arrows at the bottom of Fig. 2. This sixty cycle sawtooth sweep is broken up into three sawtooth wave forms on the screen 18 of cathode-ray tube 2, as indicated by the three groups of five vertical lines

25 each in Fig. 2. This occurs because the 180 cycle sawtooth wave signal from oscillator 24 is applied to the vertical deflection plate 12 of oscillator 2. That is, the beam 16 is deflected vertically three times during each one-sixtieth

30 second horizontal sweep, or one time each one hundred and eightieth of a second, by the sawtooth shaped impulses from oscillator 24. This is shown in Fig. 2 by three groups of vertical lines in Fig. 2, each one of these lines occurring in one nine hundredth of a second due to the 900 per second sawtooth shaped impulses from oscillator 23 being applied to vertical deflection plate 11.

35 The horizontal sweep of beam 15 of tube 1 is produced by applying a sawtooth voltage of 900 cycles from oscillator 23 to the horizontal deflection plate 10 of tube 1 by lead 29. This 900 cycles per second sweep is divided into five portions as viewed on the screen of tube 1 by applying a 4500 cycle sawtooth wave from oscillator 22 to the vertical deflection plate 8. Each one of these 4500 per second sawtooth waves is represented in Fig. 3 as a group of seven lines included between the sloping line marked "4500 saw." In turn each one of these 4500 cycle saw-

tooth waves is divided into seven individual sawtooth waves by coupling the 31,500 cycle sawtooth wave out of blocking tube oscillator 21 to the vertical deflection plate 7 of tube 1 by lead 27. Each one of these 31,500 per second sawtooth waves is represented in Fig. 3 as a group of fine dots, one of these groups being included between arrows and marked "31,500 saw."

Each 31,500 cycle sawtooth wave is modulated by coupling the 157,500 cycle sine wave output from oscillator 20 to the grid 4 of tube 1. This results in producing five alternate dark and bright spots in each one of the 31,500 cycles per second lines as shown in Fig. 3.

Another way of understanding what is depicted in Fig. 3 is by noticing that when the 900 cycle per second impulses are applied by lead 29 to the horizontal deflection plate 10, the result is a sawtooth sweep along the horizontal axis of the tube 1 at the rate of 900 cycles per second.

The 4500 cycles per second impulses from oscillator 22 which are applied to the horizontal deflection plate 8 of tube 1 produce the five rows of lines, one of these rows being marked "4500 saw." in Fig. 3.

Each one of the five 4500 cycle per second impulses is divided into seven vertical lines by the 31,500 cycle per second impulses from oscillator 21 that are applied by lead 27 to the vertical deflection plate 7. One of these lines is labelled at the upper right hand corner of Fig. 3, there being thirty-five of them for each 900 cycle per second impulse from oscillator 23.

The oscillator 20 applies a cathode-ray beam blanking signal to the grid 4 of tube 1 at one hundred fifty-seven thousand five hundred times per second. The blanking impulses produce the dots shown in Fig. 3 at this rate which is five times per impulse applied by lead 27 from oscillator 21 to plate 7 of tube 1.

Synchronizing generators are usually locked-in to the power line frequency, such as 60 cycles per second, for example. In order to check the phase relationship between the 60 cycle oscillator 25 and the power line frequency, indicated diagrammatically by block 35, the lead 36 is connected from the power line to the grid 4 of tube 2 in such a way that this grid is modulated slightly by a small portion of half of the 60 cycle power line frequency. The result of this modulation is that a small portion of the wave forms on the screen 18 of tube 2 appears slightly darkened. This darkened portion will remain in one position when lock-in prevails. When the oscillator 25 departs from the power line frequency the darkened portion will move horizontally along the wave forms indicated in Fig. 2.

It will be obvious that the signals depicted in Figs. 2 and 3 will be as shown therein, only when the oscillators 20 to 25 are firing correctly, and that since the respective signals are readily identified with respect to the oscillators which produce them any irregularity therein instantly reveals that the corresponding oscillator needs adjusting. In this way the device serves as a monitoring device by means of which much time is saved in finding where the trouble is and when the correct adjustments have been made to remedy the trouble.

What is claimed is:

1. A device for monitoring a series of connected sawtooth wave generating oscillators the frequency of each one of which is an integral multiple of a preceding one, which comprises a cathode-ray tube and a direct lead from each one of

at least three of said oscillator to a different deflection electrode of said tube.

2. A device for monitoring a series of connected sawtooth wave generating oscillators the frequency of each one of which is an integral multiple of a preceding one, which comprises a cathode-ray tube and a direct lead from each one of at least three of said oscillators to a different deflection electrode of said tube, two of said electrodes being a pair which deflect the beam of said tube in opposite directions.

3. A device for monitoring a series of connected sawtooth wave generating oscillators the frequency of each one of which is an integral multiple of a preceding one, which comprises a cathode-ray tube and a direct lead from each one of at least three of said oscillators to a different deflection electrode of said tube, two of said electrodes being a pair which deflect the beam of said tube in opposite directions and a third one being adapted to deflect said beam at an angle to the deflection of said pair.

4. A device for monitoring a series of connected sawtooth wave generating oscillators the frequency of each one of which is an integral multiple of a preceding one, which comprises a cathode-ray tube and a direct lead from each one of at least three of said oscillators to a different deflection electrode of said tube, two of said electrodes being a pair which deflect the beam of said tube in opposite directions, a third one being adapted to deflect said beam at an angle to the deflection of said pair and the fourth one being grounded.

5. A device for monitoring a series of connected sawtooth wave generating oscillators the frequency of each one of which is an integral multiple of a preceding one, which comprises a plurality of cathode-ray tubes and a lead from each one of at least five of said oscillators to a different deflection electrode of said tubes.

6. A device for monitoring a series of connected sawtooth wave generating oscillators the frequency of each one of which is an integral multiple of a preceding one, which comprises two cathode-ray tubes and a lead from each one of at least five of said oscillators to a different deflection electrode of said tubes.

7. A device for monitoring a series of connected sawtooth wave generating oscillators the frequency of each one of which is an integral multiple of a preceding one, which comprises a plurality of cathode-ray tubes and a lead from each one of at least five of said oscillators to a different deflection electrode of said tubes, one of the deflection electrodes of each one of said cathode-ray tubes being grounded.

8. A device for monitoring a series of connected sawtooth wave generating oscillators the frequency of each one of which is an integral multiple of a preceding one, which comprises a cathode-ray tube, a direct lead from each one of at least three of said oscillators to a different deflection electrode of said tube and a source of power of the same frequency as that of the lowest frequency of said oscillators connected to the control grid of said tube.

9. A device for monitoring a series of connected sawtooth wave generating oscillators the frequency of each one of which is an integral multiple of a preceding one, which comprises a plurality of cathode-ray tubes, a lead from each one of at least five of said oscillators to a different deflection electrode of said tubes and a lead from the oscillator of highest frequency of said plural-

ity of oscillators to the control grid of one of said tubes.

10. A device for monitoring a series of connected sawtooth wave generating oscillators the frequency of each one of which is an integral multiple of a preceding one, which comprises a cathode-ray tube, a direct lead from each one of at least three of said oscillators to a different deflection electrode of said tube, a source of power of the same frequency as that of the lowest frequency of said oscillators connected to the control grid of said tube and a lead from the oscillator of highest frequency of said plurality of oscillators to the control grid of one of said tubes.
